Atlys.

UNITED STATES PATENT OFFICE.

JOSEPH F. FOSTER, OF JACKMAN, MAINE.

SNOWSHOE.

Application filed November 12, 1923. Serial No. 674,217.

To all whom it may concern:

Be it known that I, JOSEPH F. FOSTER, a citizen of the United States, residing at Jackman, in the county of Somerset and State of Maine, have invented new and useful Improvements in Snowshoes, of which the following is a specification.

This invention relates to a snow shoe having a heelless foot pocket, adapted to receive the forepart of the wearer's foot and loosely connected with the snow shoe, so that the rear portion of the pocket is free to rise and fall independently of the snow shoe.

One object of the invention is to provide improved means for loosely connecting the toe portion of the pocket with the snow shoe, in such manner as to prevent objectionable endwise and sidewise displacement of the pocket, and to permit its rear portion to freely rise and fall independently.

Another object is to provide improved means for firmly securing the pocket to the wearer's foot without interfering with the upward and downward movements of the rear portion of the pocket.

I attain the above-mentioned and other related objects by the improved construction hereinafter described and claimed.

Of the accompanying drawings forming a part of this specification,—

Figure 1 is a top plan view of a snow shoe embodying the invention.

Figure 2 is an edge view of the same.

Figure 3 is a section on line 3—3 of Figure 1.

The same reference characters indicate the same parts in all of the figures.

The frame 12 and the tread portions 13 of the snow shoe may be of any suitable construction, the tread portions being composed, as usual, of interlacing thongs secured to the frame and forming open meshes. The snow shoe is provided with a heelless pocket 14, adapted to receive the forepart of the wearer's foot. Said pocket is preferably a heelless moccasin, the general construction of which is so clearly shown by the drawings that description thereof is unnecessary.

The pocket is provided with strap guides 15, at opposite sides of its toe portion, said guides being preferably leather strips united at their end portions to the sides of the pocket by stitches 16, which are spaced apart, so that a confining strap 17 may be

passed between the central portions of the members and the sides of the pocket.

The confining strap 17 extends across the toe portion of the pocket and across the confining members 15. The end portions of the strap are anchored to the snow shoe at opposite sides of the pocket, preferably by being threaded through meshes of one of the tread portions 13, as shown by Figures 1 and 2, the anchored portions being bent, as best shown by Figure 1, so that they are frictionally engaged with the thongs and are free from liability to slip lengthwise from their anchored positions.

The portion of the strap 17 between the anchored portions constitutes an arched loop, which cooperates with the retaining members 15 in loosely confining the pocket against objectionable endwise and sidewise displacement, and in permitting the rear portion of the pocket to freely rise and fall. The anchored portions may be forcibly shifted to vary the length of the loop and thus permit the rear portion of the pocket to rise variably, so that the heel portion of the foot may have any desired freedom of upward movement from the snow shoe.

When the pocket is formed as a heelless moccasin, its rear portion is adapted to be contracted about the instep portion of the wearer's foot and maintained closely contracted to prevent the admission of snow. To cause such contraction, I provide a contracting strap 20, fixed, as by rivets 21, to the rear portion of the pocket, at the lower side thereof and having free ends adapted to overlap the upper side of the pocket, the strap being provided at one end with a buckle 22, adapted to engage the other end of the strap.

To confine the foot against backward withdrawal from the pocket, I provide a heel strap 23, fixed at one end to one side of the rear portion of the pocket, and adapted to extend from that side around the heel of the wearer, and to the opposite side, where the pocket is provided with a buckle 24, adapted to engage the heel strap and maintain it suitably tensioned.

I claim:

1. A snow shoe having a heelless foot pocket bearing on a portion of the open mesh tread or filling of the shoe, said pocket being formed to receive the fore part of a foot and provided with strap guides at op-

posite sides of its toe portion, and a con-
fining strap extending across the toe por-
tion of the pocket and slidably lengthwise
in said guides, said strap having free end
5 portions each threaded through a plurality
of meshes of the said tread portion and fric-
tionally engaged with the thongs thereof to
adjustably anchor the strap ends, so that
the midlength portion of the strap consti-
10 tutes an arched loop of variable length which
cooperates with said guides in confining the
pocket against objectionable endwise and
sidewise displacement, and in permitting
the rear portion of the pocket to rise vari-
15 ably from the tread portion.

2. A snow shoe having a pocket formed as
a heelless moccasin, adapted to receive the

fore part of a foot, and adapted to be con-
tracted at its rear end portion around the
instep portion of the foot, and a contracting 20
strap embracing said rear end portion and
fixed to the lower side thereof, said strap
having free end portions overlapping the
instep portion and a buckle secured to one
end of said strap and adapted to engage the 25
other end to maintain the rear end portion
of the pocket closely contracted on the foot,
means being provided for loosely confining
the moccasin against endwise and sidewise
displacement, and permitting its rear por- 30
tion to rise and fall.

In testimony whereof I have affixed my
signature.

JOSEPH F. FOSTER.
